UNITED STATES PATENT OFFICE

102,702

DESIGN FOR AN INHALATOR

Mayo E. Roe, Elyria, and Wilbur Henry Adams,
Cleveland, Ohio, assignors to The Colson Corporation, Elyria, Ohio, a corporation of Ohio

Application October 30, 1936, Serial No. 65,611

Term of patent 7 years

To all whom it may concern:

Be it known that we, Mayo E. Roe and Wilbur Henry Adams, both citizens of the United States, residing at Elyria, in the county of Lorain and State of Ohio, and at Cleveland, in the county of Cuyahoga and State of Ohio, respectively, have invented a new, original, and ornamental Design for an Inhalator, of which the following is a specification, reference being had to the accompanying drawing forming a part thereof, in which is illustrated a perspective view of an inhalator showing my new design, the dominant features of which reside in the cabinet with handles thereon and the front panel thereof.

We claim:

The ornamental design for an inhalator substantially as shown and described.

MAYO E. ROE.
WILBUR HENRY ADAMS.
